PLAYING-CARDS.

Specification of Letters Patent. Patented Nov. 25, 1919.

Application filed March 7, 1919. Serial No. 281,130.

To all whom it may concern:

Be it known that I, ADOLPH ROSENFELD, residing at Pittsburgh, in the county of Allegheny and State of Pennsylvania, a citizen 5 of the United States, have invented or discovered certain new and useful Improvements in Playing-Cards, of which improvements the following is a specification.

My invention relates to games, and consists in a card game of novel character. The game is planned in semblance to a boxing-match; the cards, by picture, or by legend, or by both, indicate particular strokes or incidents in the progress of a boxing contest, 10 and the cards or some of them preferably bear characters of varying numerical value. It is possible to give numerical value to every card—and it is possible to give negative values to some—but I have worked out 15 a plan of the game which I prefer, and which I am about to describe, in which a part only of the cards have numerical value. It is possible also to omit from the cards characters of numerical value, and to have 20 valuation of the several cards fixed by convention, either in a set of rules, or otherwise. The game includes also, as has been indicated, rules of play, conventions, and these may conveniently be put in printed 25 form, that a set of rules may accompany each deck of cards. These rules may, of course, be so obvious, or may become so generally understood, that multiplication of them in printed form is unnecessary; but, of 30 course, in the playing of the game, conventions or rules, however simple, will be followed.

The cards—not a whole deck, but a sufficient number for present purposes—are illustrated in the accompanying sheet of drawings. Eleven cards are shown; each bears 40 a legend, such as "Clinch", "Right jab to nose", "Blocked," indicative of a stroke or incident in the progress of a boxing-match. Two of the cards bear pictorial representation 45 of the stroke, and it will be understood that either legend or picture may be alone sufficient, although I prefer that each card shall bear both picture and legend. It will 50 further be observed that some of the cards illustrated bear numerical indication of value, and others bear none. To one who understanding boxing reads the ensuing rules it will be plain that, while the actual 55 numbers given are arbitrarily fixed, the relative values reflect essential features of the sport of boxing itself. It will be plain too that the actual values may be altered and that numerical values may be given to a greater or less number of cards, even to 60 the numbering of every card in the deck. The possibility of using negative valuation for individual cards will also be plain. It should also be said again that such numbering serves merely to indicate relative 65 values; and if in legend or in picture relative value is sufficiently indicated or deductible—or if a convention in this matter lies in the rules—numbers need not appear on the cards. I prefer, however, that numbers appear. Finally, it will be noted of the cards shown in the drawing that one of them bears the legend "Counter blow" and the character "C". This feature figures, as will be found, in the ensuing rules; it is 70 a feature not essential to the game—though I prefer to employ it,—and, when used, it may be indicated on the face of individual cards in this or in other preferred manner.

The deck of cards, made up according to 80 my preference, numbers one hundred. They bear legends (or equivalent pictures or both) and valuations as follows:—

1 card "Knock out", no numerical valuation.	85
1 card "Foul blow", no numerical valuation.
15 cards "Clinch" no numerical valuation.
5 cards "Knock down" numerical valuation.	90
5 cards "Out" no numerical valuation.
5 cards "Saved by bell" no numerical valuation.
5 cards "Blocked" no numerical valuation.
5 cards "Missed" no numerical valuation.	95
10 cards for blows (i. e. bearing legend, or equivalent picture, "Hard right for mouth", "Hard left for body", etc.) Of these ten cards, two bear numerical value 1; two, 2; two, 3; two, 4; one, 5; and one, 7.	100
3 cards "Warned by referee," no numerical valuation.
45 cards to blows (i. e. bearing legend, or equivalent picture, "Right jab to nose," "A terrific right to mouth: staggering," etc.) Of these 45 cards, eight bear numerical value 1; two, 2; two, 3; three, 4; four, 5; four, 6; two, 7; two, 8; two, 9; two, 10; one, 11; four, 12; two, 13; two, 14; five, 15.	105
Total number of cards, 100.	110

Of the 45 to-blow cards, fourteen are marked Counterblow; and three more of the to-blow cards, all three bearing the numerical value 15, bear severally the additional 5 legends, "Down count 7," "Down count 8," and "Down count 9." These legends suggest that the contestant is knocked down and remains down while the referee counts 10 7, 8, or 9, but then resumes the fight; he is not knocked out.

An exemplary set of the rules of the game follows. These rules admit, as will readily be understood, of wide modification.

1. This game is known as "Boxing game 15 playing cards." It is played with one hundred cards. There are two players and no more.

2. The cards are dealt, five to each player for each round. The players in alternation 20 face the cards one by one on the table. Each card is played to the credit (or loss) of the player who faces it, and the relative standing of the two players is determined according to the legend or numerical value 25 of the successive cards. The numerical value of the card played is either added to the score of the contestant who plays it or deducted from that of his opponent, as the case may be. The player who at the end of 30 the round is numerically in the lead, or otherwise prevails, wins the round. Thus: The round begins by player A facing a card having numerical value 2; B then plays a card valued at 6. B's score stands at 4, and 35 it is A's play. If neither player scores, the round will be called even.

3. The card marked "Knock out" then played wins, not the round only, but the match; and the card marked "Foul blow" 40 loses the game for him who plays it. A player who faces in the course of one game three cards marked "Warned by referee" loses the game. Once a card marked "Warned by referee" is faced, it may be 45 thrown aside, and not returned to the deck until the match is ended.

4. If a player faces successively in one round cards marked "Knock down" and "Out"; he has played the equivalent of 50 "Knock out", and he wins the match.

5. If a player faces "Saved by bell" immediately after his adversary has faced "Knock down", the round ends. The player who faced "Knock down" cannot then face "Out." 55

6. A card marked "Counterblow" is worth one point more than is otherwise indicated as its numerical value. Such card marked "Counterblow" is good only as an exchange of blows; it is not good if played after 60 "Clinch"; "Blocked", "Missed", "Warned by referee", "Knock down", "Out", or "Down count 7", 8, or 9.

7. A card marked "Blocked" or "Missed" 65 is of value to the holder only if faced immediately after his adversary has faced a for-blow card. For example, if when A plays "Right jab for nose" with valuation of 1, B follows with "Blocked" or "Missed", A fails to retain the credit of one point 70 which otherwise he would have enjoyed.

8. A match may consist of as many rounds as may be agreed upon by the players at the outset. In order to play a fight to the finish, one player or the other must either 75 be knocked out or must lose the game in the manner indicated in Rules 3 and 4. If at the end of seven rounds (70 cards of the total 100 having then been dealt) the fight is unsettled, the cards are gathered and 80 shuffled, before dealing for the eighth round. The game then proceeds as before. The last thirty cards of the deck should never be dealt. This rule may be modified; the cards may be shuffled at the end of five rounds, or 85 at the end of any other number of rounds agreed upon.

I claim as my invention:

A card game consisting in a deck of one hundred cards, of which one card bears indication of Knock out, one of Foul blow, 90 fifteen of Clinch, five of Knock down, five of Out, five of Saved by bell, five of blocked, five of Missed, three of Warned by referee, ten of for blows, and forty-five of 95 to blows, substantially as described.

In testimony whereof I have hereunto set my hand.
